UNITED STATES PATENT OFFICE.

OWEN F. MATTINGLY, OF WASHINGTON, DISTRICT OF COLUMBIA.

SIFTER.

1,089,777.

Specification of Letters Patent. Patented Mar. 10, 1914.

Application filed July 13, 1912. Serial No. 709,228.

To all whom it may concern:

Be it known that I, OWEN FRANKLIN MATTINGLY, a citizen of the United States, residing at Washington, District of Columbia, 5 have invented certain new and useful Improvements in Sifters, of which the following is a specification.

An object of the invention is to provide a sifter for sifting or screening materials such 10 as sand, gravel, cracked stone, ashes and other like materials.

The invention comprehends among other features a device which can be conveniently transported from one place to another and 15 in which the parts composing the sifter can be readily removed for the purpose of cleaning the sifter and parts substituted when required for sifting different materials.

A further embodiment of the invention relates 20 in means whereby the inclination of the screen can be varied to suit the particular material that is to be sifted and which upon striking the screen will gravitate thereon to a discharge opening, while the finer portions 25 of the material will pass through the screen into a suitable receptacle provided therefor.

In the further disclosure of the invention reference is to be had to the accompanying drawings, constituting a part of this specification, 30 in which similar characters of reference denote corresponding parts in all the views, and in which:

Figure 1 is a side elevation. Fig. 2 is a vertical longitudinal sectional view. Fig. 3 35 is a front elevation, and Fig. 4 is a vertical transverse sectional view taken on the line 4—4 in Fig. 2.

Referring more particularly to the views use is made of a stand 10, including a body 40 11 terminating in front and rear legs 12. Mounted to swing on both sets of legs 12 are supporting members 14, having rollers 15 journaled thereon, cotter pins 16 being provided to pass through registrable apertures 45 in the front legs 12 and supporting members 14 to secure the supporting members in the vertical plane of the front legs as shown, it being readily seen that if desirable the cotter pins 16 can be removed 50 from engagement with the supporting members 14 and the said members can then be swung into an inoperative position so that either the front or rear legs 12 made to repose on the ground, thus tilting the stand 55 10 forwardly or rearwardly.

The stand 10 is provided with a plurality

of slots 17, and a casing 18 is removably mounted within the stand 10, a horizontally arranged shaft 19, having a fork-like agitator 20 thereon, being journaled on the casing 18 with the shaft 19 arranged in the slots 17 when the casing 18 is mounted within the stand, so that the said shaft will readily support the casing, as shown in the views. The shaft 19 has a crank or handle 60 portion 21 arranged exteriorly of the casing 18 and stand 10, for the purpose of operating the agitator 20 and removably mounted to repose on ledges 22 on the inner face of the sides of the casing 18 is a screen 23, the 65 said screen constituting a cover for the casing 18. The screen is removably mounted so that screens of coarse or fine mesh may be used for sifting coarse or fine materials. When mounted in the casing as mentioned, 70 the said screen will align with a discharge chute 24 projected from the front of the stand 10, a closure 25 being gravitationally mounted on the casing 18 to normally close the upper end of the discharge chute. A 75 chain 26 has connection with a staple 27 secured to the closure 25 and the said chain passes loosely through a staple 28 on the front of the casing 18, a hook 29 having connection with the free end of the chain and 80 adapted for engagement with one of the medial links of the chain 26 to permit of adjusting the closure 25 to any desired position, as will be readily discerned in the 85 views.

The casing 18 has the front and rear sides thereof inclined and converging to form a discharge chute 30, a closure 31, having an integral handle 32, being slidably mounted on the upper end of the discharge chute 30 to 90 close the same. A hood 32 is provided for removable engagement with the stand 10 and at the rear end thereof there is mounted to swing a closure 33 provided to normally close the entrance to the stand 10 and casing 18, a baffle plate 34 of a fork-like construction, being rigidly secured to an inner face of one of the sides of the hood 32 to partially restrict the entrance closed by the closure 33. The rear part 32' of the hood is 95 hinged or pivoted thereto, as at 32a, so that it may be swung open for access to the casing without removing the hood.

In the use of the device described, the entire structure is first conveyed to the place 100 of operation, a suitable handle 35 being mounted to swing on the stand 10, in order

that the operator can readily pull the sifter over the ground or floor. The material to be sifted is now fed into the sifter by passing the same through the entrance normally closed by the closure 33, the baffle plate 34 being provided to prevent too much material from entering the stand in bulk. The material will now slide down the inclined screen 23 and the finer parts of the material will sift through the screen while the coarse and larger particles continue down the screen and pass outwardly through the discharge chute 24. If any clogging of material should occur on the screen 23, the agitator is set in motion by the operator to further the advancement of the material down the screen, and by simply tilting the hood section 32 open the feed of the material may be inspected at any time and an implement inserted if necessary to loosen up any clogged mass of material which cannot be freely loosened by means of the agitator. The finer particles of the material will thus be received in the casing 18 and can be readily removed therefrom by opening the discharge chute 30, normally closed by the closure 31.

If the inclination of the screen 23 is not sufficient for the advancement of the material along the screen, or is too great for such advancement, the front or rear supporting members 14 can be quickly swung into inoperative position as mentioned heretofore, thus tilting the stand 10 forwardly or rearwardly and substantially increasing or decreasing the inclination of the screen according to the character of the material whether slow or fast feeding.

My sifter is preferably made of metal, the walls of the stand 10, casing 18 and hood 32 being made of sheet metal of a galvanized nature. It will be understood, however, that I do not limit myself to the particular construction disclosed herein and that the scope of the invention is defined by the appended claims.

Having thus described the invention what is claimed as new, is:-

1. A sifter comprising in combination, an

inclosing stand structure having shaft openings, a sifter casing loosely disposed in said stand structure and having openings adapted to register with the shaft openings in said stand and engaging the interior of said stand to hold said casing against lateral movement in said stand, a shaft journaled in said casing and stand openings and supporting the casing in said stand, a screen in said casing, an agitator mounted on said shaft in operable relation with respect to said screen, and means for operating said shaft in its bearings to actuate said agitator, substantially as described.

2. In a sifter the combination with a stand, of a casing removably mounted therein, a discharge chute on the stand, a discharge chute on the casing, a screen on the casing and alining with the discharge chute of the stand, closures for the said discharge chutes, a hood on the stand, a closure on the hood and adapted to normally close an entrance to the casing, a shaft, journaled on the said casing and engaging the stand to support the casing therein and an agitator on the said shaft and movable therewith.

3. In a sifter the combination with a stand, of a casing removably mounted therein, a discharge chute on the stand, a discharge chute on the casing, a screen on the casing and alining with the discharge chute of the stand, closures for the said discharge chutes, a hood on the stand, a closure on the hood and adapted to normally close an entrance to the casing, a shaft, journaled on the said casing and engaging the stand to support the casing therein, an agitator on the said shaft and movable therewith, and a baffle plate rigidly mounted on the said hood and projecting across the mentioned entrance to the said casing.

In testimony whereof I affix my signature in presence of two witnesses.

OWEN F. MATTINGLY.
